DESIGN FOR A TEXTILE FABRIC

Robert S. Gentile, New York, N. Y., assignor to Tabin-Picker & Company, Chicago, Ill., a corporation of Illinois

Application April 26, 1940, Serial No. 91,983

Term of patent 3½ years

all whom it may concern:

I, Robert S. Gentile, a citizen of the United States, residing in New York city, the county of New York and State of New York, have invented a new, original, and ornamental Design for a Textile Fabric, of which the following is a specification, reference being had to the accompanying drawing, forming a part hereof.

The figure of the drawing is a plan view of a textile fabric showing my design which extends across the full width of the fabric in the order shown and forms warp-wise stripes.

I claim:

The ornamental design for a textile fabric, as shown.

ROBERT S. GENTILE.
